UNITED STATES PATENT OFFICE.

EDWIN FREDERICK HUDDLE, OF MOLINE, ILLINOIS, ASSIGNOR TO DEERE & COMPANY, OF MOLINE, ILLINOIS, A CORPORATION OF ILLINOIS.

ELEVATOR-ROLL SUPPORT.

1,399,559.

Specification of Letters Patent. Patented Dec. 6, 1921.

Application filed March 8, 1920. Serial No. 364,053.

To all whom it may concern:

Be it known that I, EDWIN FREDERICK HUDDLE, a citizen of the United States, residing at Moline, in the county of Rock Island and State of Illinois, have invented certain new and useful Improvements in Elevator-Roll Supports, of which the following is a specification, reference being had therein to the accompanying drawing.

10 My invention relates to harvester binders and more particularly to the parts employed to support the upper elevator rolls, and the object of my invention is not only to provide a simple and effective support for 15 the rolls, but to make that support readily insertible for the purpose of mounting the rolls when assembling the machine and as readily removable for disconnecting them for any purpose desired.

20 Referring to the drawings in which similar numerals indicate identical parts—

Figure 1 is a rear view of a portion of the upper end of a harvester and binder elevator frame including my improvements.

25 Fig. 2 is a section on the line 2—2 of Fig. 1 with gears, sprocket and chain in place.

Fig. 3 is a view similar to Fig. 1 but with the detachable parts of my improvement removed.

30 Fig. 4 is a section on the line 4—4 of Fig. 1, and

Fig. 5 is a side elevation of the removable casting.

Normally, in the construction of the modern harvester, a solid casting is secured to the upper end of the elevator frame and the spindles of the rolls are journaled in bearings therein, so that in the event it should be necessary to remove the rolls for any reason 40 whatever the entire casting must be removed, and as other parts of the harvester are connected to the casting the removal of it means, practically, dismantling that portion of the machine. In the drawings is shown a casting 45 1 to which I secure a side 2 of the elevator frame and also binder deck 3 and a strut 4, as commonly employed in machines of this class. I cut out the casting 1 to form openings 5 and 6 of slightly larger diameter

50 than the rolls 7 and 8, shown in full lines in Figs. 2 and 4 and in dotted lines in Fig. 1, and through these openings I insert the rolls 7 and 8 which are to be supported at their farther ends by the type of

bearing ordinarily employed and not shown 55 in the drawings. The opening 6 is extended downwardly, as shown in Fig. 1, for a purpose hereinafter disclosed.

From the grainward side of the opening 5, and for substantially one half the circumference thereof, a flange 9 extends outwardly, and a similar flange 10 extends outwardly from the stubbleward side of the opening 6. After the rolls 7 and 8 are in place I support their rearward ends by a 60 member 11 which is adapted to fit snugly between the flanges 9 and 10 and is rigidly secured to the casting 1 by bolts 12 and 13. The ends of the member 11 are rounded concentrically with the openings 5 and 6 and 65 are provided respectively with bearings 14 and 15 preferably integral therewith. The rolls 7 and 8 are provided respectively with spindles 16 and 17 rigidly fixed in the ends thereof in a well known manner; the spindle 16 is rotatably journaled in a bushing 18 in the bearing 14, the latter having a notch 19 in which a projection 20, on the bushing 18, is received to hold the bushing 70 against rotary movement. The spindle 17 75 is rotatably journaled in a bushing 21 in the bearing 15, the bushing 21 being also provided with a projection 22 which extends into a notch 23 in the bearing 15 and holds the bushing 21 against rotation. The spindles 16 and 17 extend a predetermined distance outwardly from their respective bushings and for that distance are threaded to receive gears 24 and 25 respectively, the interior of the hubs thereof being threaded 80 for that purpose.

The member 11 has a downward extension 26 on which there is a stud 27 on which an idler gear 28 is mounted and in mesh with the gears 24 and 25. The stud 27 is bored to 95 form a bearing for a rod 29 having its outer end bent to form a handle 30, and carrying rigidly secured on its inner end an arm 31 to the stubbleward end of which is pivotally connected a tripping bar 32 connected to a 100 clutch, not shown in the drawings, by which the power of the bull wheel of the machine is connected or disconnected to operate the harvester mechanism in a manner well known in the art. The usual sprocket 33, 105 having the interior of its hub threaded, is also mounted on the spindle 16 and is actuated to rotate the roll 7 by a sprocket and

chain 34, and as the gears 24 and 25 are in mesh with the idler gear 28 both rolls 24 and 25 are rotated in the same direction, this construction is of the type commonly employed in the modern harvester and binder.

The parts being assembled as shown in Figs. 2 and 1 and when it is desired to disconnect the rolls for any purpose, the chain 34 is removed and the sprocket 33 and gear 24 are rotated in the direction opposite to their normal direction of rotation until freed from the spindle 16; the gear 25 is freed from the spindle 17 in a similar manner. The bolts 12 and 13 are withdrawn and the arm 31 is disconnected from the tripping bar 32, now by rotating the rod 29, until the arm 31 is in a vertical position, the member 11 is readily removable carrying with it the rod 29 and the idler gear 28, the arm 31 passing freely through the downward extension of the opening 6.

By the means heretofore described I have provided an eminently practical construction in which the frame of a harvester elevator can be fully assembled before the rolls are mounted, and in which the rolls can be removed without disconnecting the parts of the

elevator frame, a distinctly advantageous feature in machines of this class.

What I claim is—

1. In a harvester and binder, the combination with the elevator frame, of elevator rolls having spindles, a casting on the frame, openings in said casting through which the rolls are capable of being inserted or withdrawn, a member having bearings in which the spindles are supported, means on the casting to locate said member in place to close said openings, and means to secure the member rigidly to the casting.

2. In a harvester and binder, the combination with the elevator frame, of elevator rolls having spindles, a casting on the frame, openings in said casting through which the rolls are capable of being inserted or withdrawn, a flange on the grainward side of one of the openings, a similar flange on the stubward side of the second opening, a member adapted to be located in place by said flanges to close the openings, means to rigidly secure the member on the casting, and bearings on said member in which the spindles are supported.

E. FREDERICK HUDDLE.
